[57] CLAIM

The ornamental design for a sculpting tool for dentistry, as shown and described.

DESCRIPTION

FIG. 1 is a top plan view of a sculpting tool for dentistry showing our new design;

FIG. 2 is a cross-sectional view thereof, taken on line 2—2 of FIG. 1, on an enlarged scale;

FIG. 3 is a cross-sectional view thereof, taken on line 3—3 of FIG. 1, on an enlarged scale;

FIG. 4 is a cross-sectional view thereof, taken on line 4—4 of FIG. 1, on an enlarged scale;

FIG. 5 is a side elevational view thereof;

FIG. 6 is an opposite side elevational view thereof;

FIG. 7 is a front elevational view thereof, on an enlarged scale;

FIG. 8 is a rear elevational view thereof, on an enlarged scale;

FIG. 9 is a bottom view thereof; and,

FIG. 10 is a top perspective view thereof.
